FIG. 1.

FIG. 2.

FIG. 4.

INVENTOR:
Charles J. Brown
BY HIS ATTORNEY:
A. M. Larsen

FIG. 5.

UNITED STATES PATENT OFFICE.

CHARLES J. BROWN, OF RIVER FALLS, WISCONSIN.

ANTISLIPPING ATTACHMENT FOR LADDERS.

1,331,954.

Specification of Letters Patent. Patented Feb. 24, 1920.

Application filed September 8, 1919. Serial No. 322,577.

To all whom it may concern:

Be it known that I, CHARLES J. BROWN, a citizen of the United States, residing at River Falls, in the county of St. Croix and 5 State of Wisconsin, have invented a new and useful Antislipping Attachment for Ladders, of which the following is a specification.

This invention relates to ladders, and the 10 object is to provide the lower end of the ladder with improved anti-skidding means.

In the accompanying drawing, Figure 1 is a side elevation of the lower portion of the ladder equipped with my invention. Fig. 2 15 is a right hand edge view of Fig. 1 with the rubber tip and bushing removed. Fig. 3 is an enlarged section on the line 3—3 in Fig. 1. Fig. 4 is a detail side view of one of the metallic bushings used in the rubber tips of the 20 device. Fig. 5 is a modification of the bushing shown in Fig. 4.

Referring to the drawing by reference numerals, 6 designates the rails and 7 the rungs of the ladder of any description to which my 25 improvements may be applied. Upon the lower end of each rail is fitted a metallic socket 8 which is secured by a rivet 9 passed through the longer tongues 8^a of the bracket, while shorter tongues 8^b, are not riveted but 30 serve to hold the wooden rail firmly upon the base of the socket, as do also the tongues 8^a. The socket is formed with and partly of said tongues, not only with the purpose in view already mentioned but also to save material, 35 save labor in the molding, as no core is needed as in molding a pocket-shaped socket, and to facilitate the fitting of the socket onto the wood; the socket being namely cast of malleable iron with the tongues slightly 40 spread and after the socket is placed on the wood the tongues are bent or clenched close to the wood.

Secured in the depending central portion, 45 8^c of each socket is a spur 10, having screw-threads 11, a part of which may be either screwed or molded into the casting 8^c, and part of it serves to hold a bushing 12 thread- 50 ed upon it.

Said bushing is provided with external corrugations 13 upon which is tightly fitted 50 a rubber socket or tip 14. The upper end of the bushing is provided with a groove 15 for a wire ring 16 which by a chain 17 is connected to a staple 18. In the modification shown in Fig. 5 the bushing has a thread or 55 spiral rib 19 instead of the corrugations 13 and may retain the ring 16 by a plain collar 20 instead of the groove 15 in Fig. 4. As a further modification it is shown in Fig. 1 that the rails may have threaded studs, 21, 60 below the lowest rung, and to the left in said view is shown how each bushing 12 may be screwed upon one of said studs and thus hold the rubber tip out of the way when it is not 65 wanted, because the surface on which the ladder stands is such that the sharp spurs 10 will give better service.

It will thus be understood that in the use of the ladder the spurs 10 and the rubber tips 70 or caps 14 are used as anti-slipping means alternately according to the character of the surface upon which the ladder is to stand, and when the spurs are in use the rubber tips 75 are either suspended by the chains 17 so they do not get lost or the studs 21 will hold them, with or without the use of the chains. The rubber tips further serve to protect the spurs against doing injury or becoming damaged 80 during storage and transportation of the ladder.

The spurs may or may not have their upper ends formed with projections 27 to enter into the ends of the rails.

What I claim is:

The combination with the rails of a ladder, of sockets secured on the lower ends thereof and having each a downwardly extending spur with screw threads about its base, a metal bushing threaded upon said threads and a rubber cap secured about the 90 bushings and covering its lower end.

In testimony whereof I affix my signature.

CHARLES J. BROWN.
